ELECTRICAL GUN SIGHT CONTROL

Phillip Rood Wheeler, Alexandria, Va.

Application November 8, 1945, Serial No. 627,515

1 Claim. (Cl. 177—351)

(Granted under the act of March 3, 1883, as
amended April 30, 1928; 370 O. G. 757)

1

The present invention relates to potentiometers. While it has a wide range of prospective application, it is of particular utility in an indicating system of the type including means for providing a reference mark, means for deflecting the reference mark in one coordinate direction by an amount functionally related to a first electrical signal, and means for deflecting the reference mark in a second coordinate direction by an amount functionally related to a second electrical signal, whereby the reference mark is positioned in a frame of Cartesian coordinates to provide an indication. In accordance with the invention there is provided a novel control arrangement for controlling both of those deflecting means. It comprises a control member, the ultimate function of which is to order the position of the reference mark, means responsive to displacement of the control member in one coordinate for varying the first electrical signal, and means responsive to displacement of the control member in another coordinate direction for varying the second electrical signal, whereby displacement of the control member in its frame causes a corresponding displacement of the reference mark in its frame.

The present application is a continuation-in-part of my co-pending patent application Serial No. 510,403, now abandoned, filed in the United States Patent Office on November 15, 1943, and entitled Cathode-ray gun sight.

It is an object of my invention to provide a relatively simple and inexpensive potentiometer having such structure and operation that it is adjustable in two coordinates to produce deflection of a reference mark in corresponding coordinates.

For a better understanding of the present invention, together with other and further objects thereof, reference is made to the following specification, to the claim appended thereto and to the accompanying drawings in which:

Fig. 1 is a perspective view of a novel potentiometer in accordance with my invention;

Fig. 2 is a cross-sectional view of the potentiometer illustrated in Fig. 1;

Fig. 3 is an exploded view of the moving parts of the potentiometer shown in Fig. 1;

Fig. 4 illustrates the application of my improved potentiometer control arrangement to a gun sight; and

Fig. 5 illustrates the application of my improved potentiometer to a cathode-ray tube beam-positioning system.

In Fig. 1 there is disclosed a control arrangement comprising a support, a first variable voltage divider secured to said support in one coordinate, a second variable voltage divider secured to said support in another coordinate, a control member movable in both of said coordi-

nates, means actuated by said control member for adjusting said first divider in accordance with displacement of said control member in one coordinate direction, and means actuated by said control member for adjusting said second divider in accordance with displacement of said control member in another coordinate direction, each of said means being independently displaceable.

The arrangement comprises a housing 12 functioning as a supporting member and having a suitable electrical plug 13 extending from one wall thereof. Mounted within the housing are two variable voltage dividers or potentiometers 14 and 15. Potentiometer 14 is secured to the front of the housing and is adjustable in the "left-right" coordinate direction. Potentiometer 15 is secured to the right side of the housing and is adjustable in the "fore-aft" coordinate direction. Each of the potentiometers includes its individual one of sliding contacts 16, 17. Each of the sliding contacts is mounted on its individual one of movable bars 18, 19. Each of the bars is formed with a longitudinally disposed central slot 20, 21. The ends of the bar 18 are doubled back and secured to a cable 22. The ends of bar 19 are similarly secured to a cable 23.

The embodiment of my invention illustrated in Figs. 1-3 also includes a control member or knob 24. This control member is movable in two directions in its frame of Cartesian coordinates. When it is moved to the left or right it adjusts the setting of contact arm 16 on potentiometer 14 and therefore adjusts the voltage-dividing ratio of the potentiometer. Similarly, movement of knob 24 in the fore or aft direction varies the position of contact 17 on potentiometer 15 and adjusts the voltage-dividing ratio of potentiometer 15. The control knob is secured to a vertically extending shaft 25, which passes through the slots 20 and 21 in bars 18 and 19. Suitable stops 26 and 27 at the upper and lower ends, respectively, of shaft 25 prevent longitudinal movement of the shaft but permit movement thereof in any lateral direction.

When knob 24 is displaced in a direction parallel to arm 19, shaft 25 merely slidably moves within slot 21 and contact arm 17 does not move; under this assumed condition shaft 25 displaces arm 18. Additionally, movement of knob 24 in a direction parallel to bar 18 does not cause movement of contact arm 16 but does displace contact arm 17. Thus the two means for varying the settings of the potentiometers are independently movable while both are actuated by the control member 24. Suitable graduated scales are provided on the upper surface of an index member 28 secured to housing 12. Secured to control knob 24 are index pointers 29 and 30. Scale 34 is calibrated in terms of the final result of motion

of contact arm 17, whether that result involves the position of a cathode ray tube spot in one coordinate, the setting of the sight angle of a gun sight and therefore the firing range or elevation of a gun, or any similar phenomenon, depending upon the application in which the potentiometer is employed. Similarly, scale 35 is calibrated in terms of the result produced by adjustment of contact arm 16 on potentiometer 14. That may be the position of a cathode ray tube spot in another coordinate or the deflection setting of a gun sight, for example.

Cable 22 is wound around four pulleys 36 and its ends are secured together at 38. Similarly, cable 23 is wound around four pulleys 37 and its ends are secured together at 39. The pulleys are secured to shafts 40 (two of which are illustrated in Fig. 2. This arrangement of pulleys, shafts, and cables constitutes a parallel arrangement of a conventional character, similar to one extensively employed on drafting boards.

Referring now specifically to Fig. 4 of the drawing there is illustrated in schematic form a gun-sighting system in which my improved potentiometer is included for spotting purposes. This arrangement includes a lead-computing gun sight 41 of the general class shown in United States Patent No. 1,724,093, issued to Robert Kauch and Charles L. Paulus on August 13, 1929. This gun sight includes a reference mark provided by the intersection of a vertical cross-hair 42 and a horizontal cross-hair 43. The general operation of such lead-computing sights is such that when the gun sight operator superimposes the reference mark on the target the sight angle (or angle between the line of sight and the line of fire in the vertical plane) and the sight deflection angle (or deflection of the line of sight from the line of fire in the slant plane) are of the computed values appropriate to so position the line of fire that a hit should be obtained on the target. Cross-hairs 42 and 43 are individually secured to levers 44 and 45 and these levers individually constitute the pointers of galvanometers 46 and 47. The construction and operation of elements 42 to 47, inclusive, are the same as the structure and operation of the corresponding elements shown in Figs. 4 and 5 of said United States Patent No. 1,724,093, and are well known to those skilled in the art, so that further description thereof is deemed unnecessary. The galvanometers constitute the means for deflecting the reference mark provided by the cross-hairs.

Let it be assumed that gun fire is being directed to a stationary target and that the reference mark provided by the intersection of cross-hairs 42, 43 so disturbs a line of sight with reference to a line of fire that the line of fire represents the theoretically correct solution of the fire control problem posed by data available. Let it be further assumed that in spite of this apparently correct solution a series of misses is scored, as indicated by tracer fire. By watching the paths of tracers from the gun a spotter is able to ascertain in which directions the gun fire is missing the target. My improved control arrangement provides a device by which a spotter located at the gun or at some observation point remotely removed therefrom may introduce spotting corrections which disturb the line of sight with reference to the gun by a corrective amount, prompting the gunner to keep the gun bore properly directed with reference to the target and facilitate the scoring of hits.

The terminals of potentiometer 14 are coupled

to a voltage source 58, a center tap on the potentiometer being connected to a center tap on the source. Potentiometer 15 is similarly coupled to a voltage source 51. The potentials applied to galvanometer 46 comprise the drop in resistor 84 and the drop in that portion of potentiometer 14 between the contact 16 and the center tap. Similarly, galvanometer 47 is actuated by the potentials in resistor 85 and the output portion of potentiometer 15. Neglecting for the moment the operation of potentiometers 53 and 54 it will be seen that the setting of contact arm 16 on potentiometer 14 is at least in part determinative of the deflection of galvanometer 46 and the position of cross-hair 42. Likewise, the setting of contact arm 17 on potentiometer 15 is determinative at least in part of the deflection of galvanometer 47 and the resultant position of cross-hair 43. By moving control knob 24 to the left or right the operator causes cross-hair 42 to be moved to the left or right, as appropriate. Likewise, by moving control knob 24 fore or aft the spotter causes cross-hair 43 to be elevated or depressed, as appropriate. Scales 34 and 35 may therefore be calibrated in terms of the yards of range or mils of deflection, respectively, introduced by the spotting correction.

My improved control arrangement is of equal utility for introducing spotting corrections during fire on a moving target. In accordance with the teachings of United States Patent 1,724,093, hereinabove referred to, and of United States Patent No. 1,322,153; issued November 18, 1919, to J. S. Wilson and W. E. Dalby, there are included in gun sight 41 a generator 55 for generating an electrical signal proportional to the train component of the rate at which the sight tracks a target. Similarly, there is provided an elevation generator 56 for generating a voltage proportional to the elevational component of the rate at which the sight tracks the moving target. The lead angle by which the line of fire should lead the line of sight in order to produce hits on a moving target is functionally related to the product of the tracking rate and the time of flight. In practice the tracking rate is automatically established by keeping the line of sight on the target and the time of flight factor, considered to be directly proportional to range for a given anti-aircraft gun, is introduced by a range setting. For this purpose, the output circuits of generators 55 and 56 are coupled to the input circuits of potentiometers 53, 54, respectively. As a range setting expedient, the sliding contacts 55 in the output circuits of potentiometers 53 and 54 are ganged by any appropriate means indicated by the dashed line 57. The voltage outputs of potentiometers 53 and 54 for any given tracking rate are controlled in accordance with range by varying the setting of potentiometers 53 and 54. Potentiometer 53 applies to galvanometer 46 a signal proportional to the train component of the desired lead angle and potentiometer 54 applies to galvanometer 47 an electrical signal having a magnitude proportional to the elevational component of the desired lead angle. The polarities of the signal outputs of generators 55 and 56 are such that the directions of the resultant deflections of cross-hairs 42 and 43 are related to the directions of motion of the target in the train and elevational coordinates, respectively. As explained in the above-mentioned copending patent application and in the issued patents hereinabove referred to, elements 53, 54, 55, 56 and 57, in cooperation with elements 42 to 47 includ-

sive, so deflect the reference mark provided by the intersection of cross-hairs 42, 43 and cause the line of sight to be so disturbed with respect to the bore axis of the gun that the line of fire is caused to lead the line of sight by the proper computed amount (due to the action of the gunner in so moving the gun and sight as to keep the line of sight on the target).

Assuming the proper computation of the lead angle from available data, and assuming further that the spotter observes that misses are being scored, the spotter moves control knob 24 and deflects the reference mark in order to cure these errors. This is done as effectively in antiaircraft fire as in fire on a stationary target.

In Fig. 5 there is disclosed an indicating system of the cathode-ray tube type and including my improved voltage control arrangement for horizontal and vertical spot positioning. The circuit there illustrated was substantially copied from Fig. 1825, page 397, the Radio Amateur's Handbook, twentieth edition, 1943, published by the American Radio Relay League, Incorporated, West Hartford, Connecticut, so that a full description thereof is not necessary. Briefly however, there is shown a bleeder resistor comprising resistors 60 (30,000 ohms), 61 (30,000 ohms), 62 (75,000 ohms), 63 (50,000 ohms, variable), and 64 (25,000 ohms, variable). Resistors 60 to 64 are connected as a series combination and are adapted to be coupled to a 400-600 volt direct current source. The junction of resistors 60 and 61 is grounded. In shunt across this combination is a condenser 65 (8 microfarads). This bleeder resistor supplies suitable potentials to a cathode ray tube 66. The cathode of this tube is connected to the junction of resistors 63 and 64 and is therefore negatively biased with respect to ground. Since the second anode 67 of tube 66 is grounded, it is positive with respect to cathode 68. The control electrode 69 is negatively biased with respect to the cathode by connection to a sliding tap on resistor 64, through resistor 70 (300,000 ohms). The first anode 71 is positively biased with respect to the cathode by connection to a sliding tap on resistor 63. Vertical beam-deflecting plate 73 and horizontal beam-deflecting plate 74 are grounded. Tube 66 includes a fluorescent screen. The beam from the electron gun structure 68, 69, 71 and 67 causes a spot to appear on this screen. For the purpose of positioning this spot there are provided positioning controls 14, 15 in the particular form shown in Figs. 1 to 3, inclusive. The resistor portions of potentiometers 14 and 15 are connected in parallel with the series combinations of resistors 60 and 61. Suitable values for resistors 14 and 15 are one (1) megohm each. Horizontal deflecting plate 75 is connected to contact arm 16 through a resistor 77 (5 megohms) and vertical deflecting plate 76 is connected to contact arm 17 through a resistor 78 (5 megohms). Since the junction of resistor 60 and 61 is grounded deflecting plate 75 is at the same potential as deflecting plate 74 when contact arm 16 is on the central electrical point of resistor 14. Similarly, deflecting plates 73 and 76 are at the same potential when contact arm 17 is at the center of resistor 15. When contact arm 16 is moved to the left plate 75 becomes more positive than plate 74 and the electron beam, being negatively charged, is deflected to the left. Likewise, movement of contact arm 17 in the aft direction makes plate 76 more negative than plate 73 and causes the spot to be elevated. Conversely the spot is deflected to the right when arm 16

moves to the right and downwardly when arm 17 moves in the fore direction. It will be understood that elements 14 to 17 inclusive have the same reference numerals as in Figs. 1 to 3 inclusive. These positioning controls center or otherwise position the spot on the tube screen and may therefore be used as spotting controls in a cathode ray tube sight. Such a sight is described in my copending patent application hereinabove referred to. Signals representative of desired train and elevational lead components may be applied to plates 73, 76 and plates 74, 75 by input circuit conductors 81 and 82, respectively, connected to the junction of resistor 78 and deflecting plate 76 and the junction of resistor 77 and deflection plate 75, respectively.

While there has been shown and described what is at present considered to be a preferred embodiment of the present invention, it will be obvious to those skilled in the art that various changes and modifications may be made therein without departing from the true scope of the invention, and it is, accordingly, intended in the appended claim to cover all such changes and modifications as fall within the true scope of the invention and without the proper scope of the prior art. For example, my invention comprises rheostat structures as well as potentiometer structures.

The invention herein described may be manufactured and used by or for the Government of the United States of America for governmental purposes without the payment of any royalties thereon or therefor.

I claim:

In a gun mounted for training and elevation movement and having a gun sight provided with a reference mark and means for deflecting the reference mark in one coordinate direction by an amount functionally related to a first electrical signal and means for deflecting the reference mark in a second coordinate direction by an amount functionally related to a second electrical signal, whereby said reference mark is positioned in a frame of Cartesian coordinates to provide an indication the combination of, a control arrangement for adjusting both of said deflecting means comprising a manually displaceable control member, means responsive to displacement of said control member in one coordinate direction for varying said first signal and means responsive to the displacement of said control member in another coordinate direction for varying said second signal, whereby displacement of said control member in its frame causes displacement of said reference mark in its frame.

PHILLIP ROOD WHEELER.
